METHOD OF MANUFACTURING GRID ELECTRODES

Walter L. Krahl, Swampscott, Mass., assignor to
Hygrade Sylvania Corporation, Salem, Mass., a
corporation of Massachusetts

Application September 9, 1937, Serial No. 163,001

13 Claims. (Cl. 140—71)

This invention relates to methods of making grid electrodes and more particularly to grid electrodes for use in radio tubes and the like.

An object of the invention is to provide a method of making a grid electrode wherein each lateral wire or grid turn consists of an individual length of wire with the ends thereof fastened to one of the usual grid side rods, and with the median portion fastened to the other axis side rod. As a result of this method of manufacture the grid turns may be disposed parallel to each other and with the halves of each turn in the same plane.

A feature of the invention relates to a method of forming a radio tube grid employing a rotatable mandrel, and whereby the mandrel need be rotated through an angle of only 180 degrees to complete simultaneously all the grid loops or turns. As a result of this feature the grids may be made either by hand or by automatic machinery with greater speed and uniformity.

A further feature relates to the novel organization and succession of steps whereby grid electrodes for radio tubes and the like can be made in large quantities with maximum uniformity and dimensional accuracy.

Other features and advantages not specifically enumerated will be apparent after a consideration of the following detailed descriptions and the appended claims.

While the method according to the invention will be disclosed herein as employing a machine for performing certain operations, it will be obvious that grids according to the invention may be formed entirely by hand or partly by hand and partly by machine. Accordingly in the drawings,

Figs. 1 to 5 are diagrammatic views to illustrate successive steps in forming the grid electrode according to the invention.

Fig. 6 is a plan view of a grid electrode according to the invention.

Fig. 7 is an elevational view of the grid electrode of Fig. 6.

Fig. 8 is a top plan view partly in section, of a machine which may be utilized in practising the invention.

Fig. 9 is an enlarged detail view of part of the machine of Fig. 8.

Fig. 10 is a cross sectional view of Fig. 8 taken along the line 10—10 thereof.

Fig. 11 is a detail sectional view of Fig. 10 taken along the line 11—11 thereof.

Fig. 12 is a cross sectional view of Fig. 10 taken along the line 12—12 thereof.

Referring for the present to Figs. 6 and 7, the grid electrode according to the invention comprises preferably a pair of parallel uprights or metal side rods 1, 2 to which are fastened preferably by welding, a plurality of grid turns or "laterals" 3. In accordance with the invention, each turn is formed from an individual length of fine wire or ribbon bent or shaped to provide the desired contour to the body portion which body portion terminates at opposite ends in substantially U-shaped portions. While the drawings show a grid wherein the body portion is elliptical in shape it will be understood that any other contour may be provided, for example, circular, rectangular or the like. The ends 5, 6 of each turn are welded to the side rod 1, while the U-shaped median portion 7 is welded to the side rod 2. If desired, the off-set portions of each grid turn are formed with substantially straight portions 8, 9, 10, 11. By reason of the relatively sharp bend between the said straight portions and the curved body portion, the grid turns retain their desired contour. Preferably the grid turns are fastened to the side rods so that their planes are perpendicular to the plane of the side rods, thus facilitating the "shadowing" of the turns of one grid with those of a surrounding grid, for purposes well-understood in the radio tube art, for example as embodied in the type of radio tube designated generally 6L6.

Referring to Figs. 1 to 5, the method of forming the grid of Figs. 6 and 7 is substantially as follows. A plurality of rigid wires 1, 2 to constitute the side rods, are supported in any suitable manner on diametrically opposite sides of an elliptical mandrel 17, or on a mandrel of any other desired contour. Preferably this mandrel is formed of two separable halves which are provided with a suitable wedge or the like, whereby the mandrel may be expanded and collapsed to permit the shaping and removal of the finished grid. A plurality of wires or ribbons 12 (Fig. 9) from a corresponding plurality of pay-off reels 13 have their ends welded as indicated by numeral 14, to the upper face of side rod 2 (Fig. 1). Preferably, these wires are guided through a comb 15 (Fig. 9) whereby they are maintained parallel to one another and are spaced apart the required distance. The next step is to weld each wire 12 to the side rod 1, as indicated by the numeral 16 (Fig. 2), taking care that the wires are held under sufficient tension to conform them to the periphery of the mandrel. The mandrel 17 is then rotated around its axis in the direction of the arrow (Fig. 2) thus bringing the side rod 2

into the position previously occupied by side rod 1, as indicated in Fig. 3. The wires 12 are then welded to the side rod 2 as indicated by the numeral 18. Preferably instead of employing 5 a single mandrel, a pair of spaced mandrels 17 and 19 are employed, so that at the same time the grid wires are welded to the side rod 1 on mandrel 17 (Fig. 3) they can be simultaneously welded to the side rod 2^a which has been previously loaded into the mandrel 19. At this stage 10 of the process the grid wires are therefore completely looped around the grid side rods 1, 2 on mandrel 17 and are fastened to the side rods 1 and 2 as well as to the side rod 1^a on the next 15 mandrel.

The next step is the severing of the grid wires between the two mandrels as indicated diagrammatically by the cutting members 20, 21 (Fig. 4). Preferably, the cutting edges are designed so that 20 the grid wires are severed as close as possible to the respective side rods. The mandrel 17 with the completely formed grid therein is next expanded against a suitable die whereby the grid loops are formed to the desired contour, such for 25 example as illustrated in enlarged form in Fig. 6. While the grid on mandrel 17 is being formed, the next mandrel 19 of the pair is moved to the position previously occupied by mandrel 17 and the wires 12 are welded to the side rod 2^a as indicated by the numeral 22 (Fig. 4). Thereafter the mandrel 19 is rotated through an angle 30 of 180 degrees to the position shown in Fig. 5 whereupon the wires 12 are welded to the side rod 2^a as indicated by the numeral 23. The grid 35 on mandrel 19 is then expanded and shaped as already described for mandrel 17. After the formation and shaping of the grids as described, the mandrels are collapsed by removing for example the wedge 24, whereupon the grids may be 40 easily removed.

From the foregoing description, it will be seen that the grids are formed merely by rotating each mandrel through an angle of 180 degrees, and the various grid wires or laterals are all simultaneously fastened to the respective side rods and are simultaneously formed around the respective mandrels, thus insuring accuracy of spacing between the various wires and expediting the formation of the finished grids. Furthermore, each 45 grid wire is fastened intermediate its ends by means of an offset portion, to one side rod and the ends of each turn are fastened at opposite sides of the other side rod, thus enabling the grid wires to be properly shaped and to retain 50 their shaped form since the offset portions of each grid wire are conformed to the periphery of the side rods.

Referring to Figs. 8, 9, 10 and 11 a description 55 will now be given of the more important parts of a typical mechanism for forming the grids of Figs. 6 and 7. The machine comprises a main horizontal shaft 40 carrying a circular plate 41 and to which is attached a drum 35. Plate 41 is adapted to be rotated in a step-by-step manner 60 by any suitable means to twelve different positions, for example by a Geneva movement including a revolving pin 30 and cooperating slots 30^a in plate 41. Supported in drum 35 and for individual rotation are twelve grid mandrels designated A to L consecutively. In order to simplify 65 the description, it will be assumed that the position in which mandrel A is shown in Fig. 8 is position #1, mandrel B is position #2 and likewise for the remaining mandrels. As shown in 70 detail in Fig. 10, each mandrel is split through-

out its length so as to enable a wedge 24 to be inserted between the halves of the mandrel for the purpose of expanding the grid turns formed thereon as described hereinbelow. Normally, that is with the wedge withdrawn, the mandrel halves lie flat against each other so that their combined outer peripheries provide the proper contour for the grid turns to be formed thereon. As shown more clearly in Figs. 8 and 11, each mandrel is provided on opposite diameters with 10 a pair of longitudinal grooves to receive the grid side rods. In order to prevent the mandrels sliding in the drum 35 in a direction parallel to their major axes each is provided with a pair of plates 39, 43 which fit in a peripheral groove 15 around the end of the mandrel as shown in Fig. 10. Each mandrel is designed to be rotated around its major axis when the mandrel reaches the proper position in the indexing movement of the drum 35, and in order to prevent accidental rotation at other positions, each mandrel is provided at the bearing end portions 33, 34 with depressions which register with the balls 37 spring-pressed by springs 38 (Figs. 10 and 11). The ends 33, 34 of each mandrel are slightly 20 larger in cross section than the winding portion M—M' of the mandrel, and are preferably equal to the major axis of the finished grid. The grooves in the mandrel which receive the grid side rods are of different depth along the 25 mandrel length. For example the depth of each groove between the points M—M' is such as to surround less than 180 degrees of the side rod periphery so that more than one half of the side rod periphery protrudes above the surface 30 of the mandrel. The portion of the mandrel grooves between the point M' and the upper end of the grooves is gradually deepened so that at this portion the grooves surround practically the entire periphery of the side rods, thus providing a "chuck" hold on the side rods at their 35 upper ends (Fig. 10). Thus when the side rods are loaded into the mandrels they are clamped between the portions 33, 34.

Referring to Figs. 8 and 10, the drum 35 has 40 twelve slots 36 in its surface, one for each mandrel, each slot having a width equal to the width of the major diameter of the associated mandrel, and the inner end of each slot being semi-circular to correspond with the curvature of the 45 mandrel ends 33, 34. Slidably mounted in each slot is a plate 21^a normally held against the bearing portions 33, 34 of the mandrel by a stationary ring 20^a. The slideable plates 21^a are semi-circularly concave at their inner ends to 50 conform to the curvature of the bearing ends 33, 34 of the mandrel. Thus one half of the bearing for each mandrel is provided by an associated slide 21^a, and the other half is provided by the cooperating semi-circular cut-out in 55 drum 35.

Referring more particularly to Fig. 8, the drum with its mandrels is arranged to form simultaneously, two sets of grids, thus while one set is being formed on mandrels A to F, a second set 60 is being formed on mandrels G to L. This allows grids of different numbers of turns or grids of different pitches to be formed on the same machine. For this purpose, there are mounted adjacent the drum 35 two series of pay-off reels 65 13, the wires 12 from which are guided by a comb or a grooved roller 15 attached by a suitable bracket to ring 20^a. When the drum is in the position shown in Fig. 8, the side rods 1 and 70 2 are guided or placed in the adjacent grooves 75

in mandrels B and A. Since any well-known wire feeding and guiding means may be employed for loading the side rods into the mandrel grooves detailed description thereof is not necessary. Likewise after the side rods are loaded into the mandrel grooves they are cut to the proper length by any well-known cutting mechanism (not shown). If desired suitable springs (not shown) may bear against the side rods to hold them in the mandrel grooves against accidental sliding movement along the mandrel.

When the side rods 1 and 2 have been loaded into the mandrels in position #1, the drum is indexed one step in the direction of the arrow by members 30, 31 (Fig. 10), thus bringing the previously loaded mandrels B and A into position #2. In this second position, the wire strands 12 from reels 13 are fed through the guides 15 and are welded to side rod 2 by means of welding jaws 18^a and 22^a which are closed on to side rod 2 by any suitable operating mechanism such as a sliding wedge or the like (not shown). In the meantime of course another set of side rods 1, 2 have been loaded into the mandrels A and L as above described for mandrels B and A. In starting the machine, the wire strands 12 may be fastened to the side rod 1 that happens to be in the position of mandrel C, but when the machine is started in operation the fastening to the side rods 2 on successive mandrels will be effected automatically. The drum is next indexed to its third position to bring the mandrel B carrying side rods 1 and 2, into the position previously occupied by mandrel C. In this position the welding jaws 18^a and 23^a are closed against side rod 1 thus welding the strands 12 thereto. It will be noted that by reason of the angle at which the wire strands are fed to the mandrels and by reason of the rotation of the drum, as the mandrel is moved from position #2 to position #3 the strands are under sufficient tension to conform them closely to the contour of one half of the mandrel.

When the welding of the wire strands on side rod 1 is completed, the jaws 18^a and 23^a are retracted. Preferably, however, jaw 18^a is moved back to its normal position as shown in Fig. 8, but jaw 23^a is moved back only sufficiently to clear the side rods on the mandrel in position #3 when the latter is rotated about its longitudinal axis in the direction of the arrow as will now be described. For this latter purpose, there is provided a bushing 42 which is slidably keyed on shaft 42^a and is adapted to be raised and lowered on said shaft at the proper interval by means of an operating arm 42^b. Shaft 42^a is arranged to be rotated through an angle of 180 degrees at the proper time with relation to the indexing movement of the drum 35, by any well-known means, for example by a gear 42^c and a cooperating segmental gear 42^d, the latter being moved into engagement with gear 42^c when the mandrel reaches position #3 and after the bushing 42 has been coupled to the end of the mandrel as shown in Fig. 10. Preferably as shown in Fig. 12 the wall of the bushing 42 is provided with diametrically opposite grooves to accommodate the side rods 1 and 2.

After the jaws 18^a and 23^a are retracted, the arm 42^b is operated to couple the mandrel to the shaft 42^a whereby the mandrel is rotated about its longitudinal axis through an angle of 180 degrees, whereupon the shaft 42^a is uncoupled from the mandrel. By suitable timing cams or the like (not shown), the jaws 23^a and 18^a are again

closed to weld the strands 12 to the side rod 2 at the points 18 (Fig. 3). At this time also the jaws 18^a and 22^a are closed upon the side rod 2 of the next succeeding grid which is now in position #2.

The drum 35 is next indexed to bring the completely welded grid into position #4, whereupon the sliding members 24^a, 26 and 27 are moved to clamp the adjacent side rods of the grids on adjacent mandrels C and D. For this purpose, it will be noted that the member 27 is provided with spaced clamping jaws 27^a, 27^b which cooperate with the corresponding clamping edges of members 24^a and 26. It will also be noted that the faces of members 24^a and 26 as well as the faces of members 22 and 23 are curved to correspond with the curvature of the mandrel. While the side rods are clamped by members 27^a—24 and 27^b—26, the cutter 25 is forced between the two adjacent clamped side rods on mandrels C and D to sever the completely formed grid on mandrel D from the half-formed grid on mandrel C.

Drum 35 is next indexed to position #5 where the wedge 24 (Fig. 10) is inserted between the two halves of the mandrel under control of a suitable timing cam (not shown). In this position of the drum, as well as in positions 2, 3 and 4, the stationary ring 20^a is cut away so that the sliding members 21^a can move radially away from the center of the drum, thus permitting the mandrel to expand upon the insertion of wedge 24. The sliding sections 21^a when they register with the cutout section of ring 20^a are held resiliently in place by means of the ring sections 31 which are normally disposed so that the high part of the curved inner face 31^a extends inwardly beyond the inner face of ring 21^a. For this purpose each section 31 carries a pin 31^b which is arranged to slide in a bracket 28 fastened to ring 20^a. A spring 29 bears against the member 31 and provides a resilient backing therefor when engaged by the curved outer faces of slides 21^a. Corresponding members to member 31 are provided in positions B, C and D so that when the welding electrodes 18^a, 22^a—23^a and the clamping jaws 27^a—27^b, 24^a, 25 engage the respective grid side rods the mandrels are capable of moving radially away from the center of the drum through a small distance, thus rigidly clamping the side rods during the welding and cutting operations.

After the wedge 24 has been inserted between the two halves of the mandrel in position #5, and after it has been removed, the mandrel contracts, but the wire strands have been given a permanent set and have been stretched so that the grid turns are slightly larger than the mandrel. The drum is then indexed to position #6 wherein a pair of pincer-like jaws (not shown) grasp the finished grid side rods which extend beyond the end of the mandrel, whereupon the jaws are retracted to strip the grid from its mandrel. The finished grid is then dropped into a suitable conveyor or container.

When the drum reaches position #7, side rods are inserted and cut to length exactly as described in connection with mandrels A and B (positions 1 and 2), and the foregoing cycle of operations of winding, welding, severing and expanding the grid turns, and the stripping of the finished grid from its mandrel is repeated in positions 7 to 12 inclusive. The grids formed in positions 7 to 12 may have different strand spacings, or different strands pitches or gauges from those being formed in positions 1 to 6, thus allowing grids of different mechanical and electrical characteristics to be made on the same machine. Preferably

the machine is so designed that when the mandrels are mounted in a circle as shown, the adjacent grid side rods on adjacent mandrels are so close together, that it is merely necessary to shear the strands 12 once between the mandrels, rather than to separate the mandrels and requiring the cutting of the strands twice between adjacent side rods.

What I claim is:

- 10 1. The method of forming a grid electrode for an electric discharge tube which comprises supporting a pair of grid side rods on a mandrel, fastening simultaneously a plurality of grid strands to one of the side rods, conforming the fastened strands around one side of the mandrel, fastening said strands to the other side rod, rotating the mandrel with the fastened strands, and then fastening said strands to the first-mentioned side rod.
- 20 2. The method of forming a grid electrode for an electric discharge tube which comprises supporting a pair of grid side rods on a mandrel, supporting a plurality of grid strands in substantially the same plane and transversely to said side rods, conforming the strands around one half of the mandrel, fastening the strands to the first side rod and to the second side rod, rotating the mandrel with the fastened strands around the mandrel axis, and then fastening the strands to the first side rod.
- 30 3. The method of forming a grid for an electrode discharge tube which comprises supporting a pair of grid side rods on opposite sides of a mandrel, fastening a plurality of grid strands to one of said side rods, moving the mandrel bodily with the fastened strands and then fastening the strands to the other side rod, rotating the mandrel with the fastened turns in a direction so as to wrap the fastened strands around the mandrel and then fastening the strands to said one of said side rods.
- 40 4. The method according to claim 1 in which the strands are severed adjacent the first side rod after the third fastening operation.
- 45 5. The method of forming a grid for an electric discharge tube which comprises supporting a pair of grid side rods on a mandrel, fastening simultaneously a plurality of grid strands to the first side rod, bending said strands around one half of the mandrel without rotating the mandrel about its own axis, fastening the strands to the second side rod, rotating the mandrel with the fastened turns through an angle of 180 degrees, and then fastening said strands to said first side rod.
- 55 6. The method of forming a grid for an electron discharge tube which comprises, supporting a pair of grid side rods on a mandrel, welding a plurality of wires from a plurality of pay-off reels to the first side rod, revolving said mandrel and side rods about a central axis in a direction to unreel predetermined lengths of wire from said reels, conforming said lengths to one half of the mandrel, welding said wires to the second side rod, rotating the mandrel around its own axis, and welding said wires to said first side rod.
7. The method of forming a grid for an electron discharge tube which comprises, supporting a pair of grid side rods on a mandrel, supporting another pair of grid side rods on a second mandrel, fastening a plurality of grid strands to the first side rod of the first pair of side rods, fastening the strands to the second side rod of the first pair of side rods, rotating the mandrel and the first pair of side rods through an angle of 180 degrees, fastening said strands to the first side rod of the first pair and to the first side rod of the second pair, and then severing the strands between the first side rod of the first pair and the first side rod of the second pair.
- 10 8. The method of forming a grid electrode for an electric discharge tube which comprises, fastening a plurality of substantially parallel grid strands simultaneously to a first grid side rod, fastening said strands simultaneously to a second grid side rod, rotating the side rods about their common axis to bring the first side rod into the position previously occupied by the second side rod, fastening the strands simultaneously to said first side rod, and expanding the portions of the strands between the side rods to form individual grid loops.
- 15 9. The method according to claim 8 in which the strands are expanded against a pair of channeled members while the side rods are clamped between the said members.
- 20 10. The method of making a grid electrode which includes the steps of supporting a plurality of pairs of grid side rods on a pair of adjacent spaced mandrels, welding a plurality of grid strands to the first side rod on the first mandrel, moving the first mandrel with the welded strands bodily at an angle to the strands to shape the strands around one half of the first mandrel, welding the strands to the second side rod on the first mandrel, rotating the first mandrel about its own longitudinal axis through an angle of 180 degrees to shape the strands around the other half of the first mandrel, welding said strands to said first side rod and also welding said strands to the first side rod on the second mandrel, and severing the strands between the adjacent side rods on the two mandrels.
- 25 11. The method according to claim 10 in which the second welding of the strands to the first side rod on the first mandrel is effected on the opposite side of the said first side rod from that where the first welding is effected.
- 30 12. The method according to claim 10 in which after severing the strands between the mandrels, the first mandrel is expanded to shape the strands around the side rods.
- 35 13. The method according to claim 10 in which the strands are shaped to provide substantially U-shaped extensions where they surround the side rods.

WALTER L. KRAHL.
